UNITED STATES PATENT OFFICE.

OTTO A. MOLDENHAUER, OF WATERTOWN, WISCONSIN, ASSIGNOR TO WISCONSIN SANITARY COW-MILKER CO., OF WATERTOWN, WISCONSIN, A CORPORATION OF WISCONSIN.

SUCTION-CUP FOR MILKING-MACHINES.

1,105,681.

Specification of Letters Patent.

Patented Aug. 4, 1914.

Application filed April 28, 1913. Serial No. 704,019.

To all whom it may concern:

Be it known that I, OTTO A. MOLDENHAUER, a citizen of the United States, residing at Watertown, county of Jefferson, and 5 State of Wisconsin, have invented new and useful Improvements in Suction-Cups for Milking-Machines, of which the following is a specification.

My invention relates to improvements in 10 suction cups for milking machines, with especial reference to milking machines of the general type shown and described in my former Patent Number 887,212, dated May 12, 1908.

15 The object of this invention is to provide a form of construction in which the teat will be expanded during the suction interval instead of being compressed or constricted as is the case with the suction cups heretofore 20 in common use. Also to provide simple and effective means whereby abnormal distention of and injury to the teat will be avoided. Also to provide simple and inexpensive means for adapting the cup for teats of various sizes, regard being also had for sanitation and the number of parts to the device 25 being therefore reduced to the minimum and so arranged that they can be readily separated and cleansed.

30 In the drawings—Figure 1 is a vertical sectional view of a cup embodying my invention. Figs. 2, 3 and 4 are detail vertical sectional views illustrating interchangeable teat engaging members.

35 Like parts are identified by the same reference characters throughout the several views.

The body A of my improved cup is provided with a removable upper section or 40 mouth piece B, which is preferably screwed to the outer surface of the body A near its upper end. The body wall is provided with an exterior shoulder at C, above which the wall of the body is made comparatively thin 45 and provided with one or more perforations D communicating between the interior of the cup and the annular space formed between this thinner portion of the wall and the removable section B. At the upper mar-

gin of the body wall, it is provided with an 50 inturned flange E.

A collar F, provided with upwardly turned flanges G at top and bottom, receives a flexible lining member H which preferably comprises a piece of rubber tubing inserted 55 through the collar F and having its ends bent outwardly and engaged over the flanges G, as shown, whereby the tubing is held in position upon the collar by its own resiliency. The tubing is normally of less diameter than the diameter of the collar F, so that its central portion bulges inwardly 60 from the collar, leaving a cavity H' between the collar and the tubing. The collar is provided with apertures F', which communicate 65 between the cavity H' and the cavity G' between the collar and the annular wall of the member H. At its upper end, the section B is provided with an inturned flange B' which serves as a clamping member for 70 the collar F, a washer I being preferably interposed in a position to bear upon that portion of the rubber lining member H which is also interposed between the flange B' and the collar F. A suction tube J leads outwardly 75 and preferably downwardly from the cavity G' through the wall of the section B of the cup, and a flexible hose pipe K will be connected to the lower end of the member J, the suction being applied through the hose K 80 and the milk being also withdrawn there-through.

With the above described construction, a pulsating or intermittent suction may be applied by means similar to that shown and 85 described in my above mentioned former patent, but with a different effect within the cup. Owing to the fact that in my improved cup the bottom is closed and the suction applied to the interior of the cup 90 through the holes D, it is obvious that the cup will first fill with milk at least to the level of the holes D. During the suction interval, the vacuum will be most pronounced in the cavities G' and H'. The walls of the 95 flexible teat engaging member H will therefore be drawn outwardly during the suction interval, substantially relieving the pressure

upon the teat and allowing it to expand for a free passage of milk through the milk duct. During this suction interval, the partial vacuum created within the cup will tend to draw it upwardly and will thus prevent it from disengaging or admitting air through its upper end. As soon as the suction is relieved, the wall H moves inwardly and applies a gentle pressure annularly to the upper portion of the teat which also tends to expel the milk therefrom.

To adapt the device for teats of different sizes, I employ interchangeable collars F, f and f', as shown in Figs. 2, 3 and 4. These collars are all exactly alike except that they are of different diameters and are provided with flanges G, g and g' of different widths. The circular outer margins of the flanges G, g and g' are all substantially the same diameter so that any one of these collars may be clamped between the flanges B' and E. To substitute one collar for another, therefore, it is merely necessary to unscrew the section B from the body section A of the cup, remove the collar F from the section B, and insert a collar of different diameter, each of said collars being provided with a flexible compression member H, as above described. The sections A and B will then be again screwed together until the substitute collar is securely clamped in position with sufficient pressure to render the same air tight at the joints, the member H serving as a packing where it extends over the surfaces of the collar flanges.

It will be observed that the milk must pass through the holes D into the cavity G' in order to reach the outlet duct J. It is therefore obvious that the degree of vacuum will be greater in the cavities G' and H' than it is in the interior of the cup. The difference in the degree of vacuum established in these cavities and that established in the cup will depend largely upon the relative capacity of the holes D and that of the suction tube or duct J. But even if the holes D are large, the vacuum will still be greatest in the cavities G' and H', and will be established first in those cavities when the suction is applied. The cup being full of milk, there will be no tendency to expand the lower portion of the teat and very little tendency to draw it downwardly into the cup, although there will, of course, be a slight downward pull. In this respect, my invention differs from all ordinary suction cups in which there is a strong downward pull exerted upon the teat which frequently draws it into the outlet and causes serious injury. Owing to the fact that the vacuum is first established in the cavities G' and H', it is obvious that the annular pressure of the member H upon the teat will be relieved before the suction is applied within the cup through the holes D.

I claim—

1. A closed bottom suction cup for milking machines, having a flexible teat engaging annulus in its upper portion, the upper and lower margins of which are expanded outwardly and secured to the cup, said cup having an outlet in its upper portion and having a suction cavity exterior to said annulus affording communication between the outlet and the lower portion of the cup.

2. A suction cup for milking machines, having a collar removably secured in its upper end portion, and a flexible teat engaging member extending through the collar, with its ends expanded outwardly and secured thereto,—said cup being closed in its bottom portion and having a suction outlet leading from its upper portion.

3. The combination with a suction cup for milking machines, having a closed bottom portion, of a set of removable teat engaging members of different diameters, each comprising a rigid annular support adapted to be secured to said cup, and a flexible wall of less diameter extending therethrough and having its ends expanded and secured to said support.

4. The combination with a suction cup for milking machines, having a closed bottom portion, of a set of removable teat engaging members of different diameters, each comprising a rigid annular support adapted to be secured to said cup, and a flexible wall of less diameter extending therethrough and having its ends expanded and secured to said support, together with means for applying suction to said cup at a point exterior to said flexible wall.

5. A suction cup for milking machines comprising a set of sections and closed at its lower end, the upper section having a suction outlet, and a teat engaging member within the upper section adapted to expand when action is applied at the outlet.

6. A suction cup closed in its bottom portion and provided with an outlet near its upper end, said cup having an expandible member in its upper portion adapted to engage a teat, and a suction duct for applying suction through said outlet and along the exterior wall of said expandible member to expand the same during the suction interval.

7. A suction cup having an annular cavity encircling its upper end portion and provided with an outlet, and a flexible lining wall for said cavity, the wall of said cup, below the lining wall, provided with apertures leading into said cavity and so proportioned to the outlet as to secure a greater degree of vacuum in the cavity than in the body of the cup.

8. A suction cup provided with a teat compressing annulus in its upper portion,

having its upper and lower margins secured to the cup, and means for expanding the central portion of said annulus radially during the milk withdrawing interval.

- 5 9. A suction cup having a tubular member extending downwardly therein, and provided with a teat compressing annulus, and means for expanding the central portion of said annulus radially during a suction in-

terval,—said cup being closed at its bottom 10 and provided with a suction outlet above the lower end of said tubular member.

In testimony whereof I affix my signature in the presence of two witnesses.

OTTO A. MOLDENHAUER.
